UNITED STATES PATENT OFFICE.

NIS JOHNSON, OF MERIDEN, CONNECTICUT, ASSIGNOR TO THE MERIDEN BRONZE COMPANY, OF SAME PLACE.

EXTENSIBLE STANDARD FOR PIANO-LAMPS.

SPECIFICATION forming part of Letters Patent No. 453,865, dated June 9, 1891.

Application filed July 17, 1890. Serial No. 359,032. (No model.)

To all whom it may concern:

Be it known that I, NIS JOHNSON, of Meriden, in the county of New Haven and State of Connecticut, have invented a new Improvement 5 in Extensible Standards for Piano-Lamps; and I do hereby declare the following, when taken in connection with accompanying drawings and the letters of reference marked thereon, to be a full, clear, and exact 10 description of the same, and which said drawings constitute part of this specification, and represent, in—

Figure 1, a view in vertical central section of an extensible standard constructed in accordance with my invention; Fig. 2, a detached view in side elevation of one of the friction-plates. Fig. 3 is a section on line xx of Fig. 1.

My invention relates to an improvement in 20 extensible standards for piano-lamps, the object being to produce a simple, reliable, and effective friction-clutch for sustaining the inner tube of the device in its adjusted position under the weight of the lamp and the lamp- 25 shade.

With these ends in view my invention consists in the construction hereinafter described, and particularly recited in the claims.

Under my invention the lower end of the 30 inner tube A terminates in a cone B, in this instance formed by a plug inserted thereto. Upon this cone two longitudinally and laterally movable tapering concavo-convex friction-plates C C have bearing, and are 35 moved up and down over the same for engaging them with and disengaging them from the walls of the stationary outer tubes of the standard. Each of the said plates has a perforation E formed in its narrower lower end 40 to adapt them to respectively receive pins F F, radially projecting from opposite points in the periphery of a collar G, and made long enough to permit the plates to move laterally upon them, but of course within narrow limits. 45 The outer faces of the said plates are countersunk around their perforations to permit the ends of the pins to be headed down to prevent the plates from dropping off when the inner tube is pulled out of the outer tube. 50 By thus attaching the plates to the said collar G their free upper ends are allowed consid-

erable lateral play toward and away from each other. The said collar is adjustably mounted upon the threaded lower end A of the operating-rod II, which is located in the 55 inner tube and projects through and below the cone E, in which it has bearing. By adjusting the collar upon this rod, as provided for, the friction-plates may be raised or lowered with respect to the cone, as may be required to compensate for wear, or to increase or diminish the friction between the plates and the outer tube. When the plates are longitudinally raised with respect to the cone, 60 the same will separate their upper ends and cause them to engage with the inner walls of the outer tube, whereby the two tubes are frictionally coupled together; but when the plates are lowered, whereby their upper ends are 65 brought into range with a smaller part of the cone, they will move toward each other and release their grip upon the outer tube and permit the inner tube to be freely raised or lowered, as desired. As the two tubes are normally coupled when the standard is in use, 70 the plates will necessarily be normally sustained in their lifted positions.

The particular means employed for moving the operating-rod longitudinally to shift the 75 positions of the plates as desired and for sustaining them in their lifted positions may vary, and I do not confine myself to any particular construction or arrangement of devices for the purpose.

As herein shown, a hand-lever I, pivoted in 80 a terminal J, secured to a threaded plug K, located in the upper end of the inner tube, is provided at its inner end with a cam L, which, when the outer end of the lever is depressed, 85 engages with a fixed collar M, secured to the upper end of the rod II and moves the same downward against the tension of a spiral spring N, encircling the rod and interposed between the said fixed collar and the upper end of the cone B and operating to automatically lift the rod and recouple the two tubes 90 after the outer end of the hand-lever has been relieved of pressure and to sustain the rod in its elevated position, and hence the plates in 95 their operative positions.

If desired, the spring may be located at the lower end of the rod and the hand-lever may 100

be replaced by a sliding collar encircling the upper end of the inner tube. I would therefore have it understood that I do not limit myself to the exact construction herein shown 5 and described, but hold myself at liberty to make such changes and alterations as fairly fall within the spirit and scope of my invention.

Having fully described my invention, what 10 I claim as new, and desire to secure by Letters Patent, is—

1. In an extensible standard for piano-lamps, the combination, with the outer tube thereof, of an inner tube terminating at its lower end in an inverted cone, a longitudinally-movable operating-rod located in the inner tube and projecting below the cone-shaped end thereof, two concavo-convex friction-plates hung to the lower end of said rod and 20 extending upward upon opposite sides of the said cone portion of the inner tube, a spring adapted to normally sustain said rod in its raised position and draw the said friction-plates upon the said cone and against the in-

side of the outer tube, and means, substantially such as described, for depressing said rod and plates against the force of said spring, substantially as described. 25

2. In an extensible standard for piano-lamps, the combination, with the outer tube 30 thereof, of an inner tube located in the outer tube and terminating at its lower end in a cone, an operating-rod located in the inner tube and projecting below the lower end thereof, a collar adjustably mounted on said 35 projecting end of the rod and provided at opposite points in its periphery with pins, two tapering concavo-convex friction-plates bearing on the said cone and laterally movable on the said pins, which enter perforations in their lower ends, a spring for lifting the rod to hold the plates normally apart, and means for manually depressing the rod against the tension of the spring, substantially as described. 40

NIS JOHNSON.
